UNITED STATES PATENT OFFICE.

ISIDOR BOORER, OF NEW YORK, N. Y.

JEWELER'S HEATING AND LIGHTING BURNER.

SPECIFICATION forming part of Letters Patent No. 625,242, dated May 16, 1899.

Application filed July 8, 1898. Serial No. 685,410. (No model.)

To all whom it may concern:

Be it known that I, ISIDOR BOORER, a subject of the Czar of Russia, residing at New York, in the borough of Manhattan and State 5 of New York, have invented certain new and useful Improvements in Jewelers' Heating and Lighting Burners, of which the following is a specification.

This invention relates to a jeweler's heating and lighting burner; and the object of the same is to provide burners for furnishing both light and heat for jewelers and others.

A further object of the invention is to so mount the gas-brackets of such heat and illuminating burners on their support as that either can be moved to any desired position independently of the other; and a still further object of the invention is to do away with the ordinary gas-cock by swiveling the burner 20 in the gas-bracket and arranging thereon a button or disk, whereby the burner-tube is adapted to be rotated on its axis into open or closed position.

The invention consists, broadly, of a suitable support connected with a gas-supply pipe and provided with a bearing-sleeve, a gas-bracket provided with alined hollow journals extending in opposite directions, one of the same being journaled in the bearing-sleeve, 25 a burner mounted on said gas-bracket, and an additional gas-bracket provided with a burner and swiveled on the other journal of the first gas-bracket.

The invention further consists of suitable features of construction and combinations of parts to be hereinafter described and then particularly claimed.

In the accompanying drawings, Figure 1 represents a side elevation of my improved 40 jeweler's heating and lighting burner. Fig. 2 is a plan view of the same, showing the heating and illuminating burners in one position in full lines and in another position in dotted lines. Fig. 3 is a detail transverse vertical 45 section, parts broken away, on the line 3 3, Fig. 2; and Fig. 4 is a transverse section on line 4 4, Fig. 3.

Similar letters of reference indicate corresponding parts.

Referring to the drawings, A indicates a suitable pedestal, which is hollow and connected with a gas-supply pipe A'. Rising

upwardly from the upper end of the pedestal A are outwardly-curved branch pipes a, which lead to a central bearing-sleeve B. It is evident that in place of such specific construction any suitable support provided with a bearing-sleeve may be employed. A radial gas-bracket D is provided at its inner end with two alined and oppositely-projecting 55 journals d d', of which d' is journaled or swiveled in said bearing-sleeve B. To connect the gas-bracket D with the bearing-sleeve B so that it will rotate therein and yet not be accidentally removed therefrom, a suitable 60 screw C is secured thereto over a washer C'. The other journal d furnishes a bearing for a sleeve E' on the inner end of a radial gas-bracket E, said sleeve being secured to said journal by means of a suitable screw e, which 65 is applied over a washer e', this construction permitting the gas-bracket E to be rotated or turned upon the journal d, while in like manner the gas-bracket D can be rotated, in turn, around the bearing-sleeve B. The head D', 70 into which the gas-bracket D is screwed and from which the journals d d' extend, is provided with an axial bore d², extending into said journals, while from the opposite ends of said bore d² openings d³ d⁴ establish a communication with the passage through the gas-bracket E with the branch tubes a, as clearly 75 shown in Fig. 3. The head D', at the mid-length of the bore d², is furthermore provided with a lateral opening d⁵, which communicates 80 with the passage through the gas-bracket D.

Onto the gas-bracket D is screwed a suitable sleeve F, which furnishes a bearing for the swivel F' of a Bunsen or equivalent heat-furnishing burner G, the said journal and 85 burner being held to said sleeve so that they can rotate therein by means of a screw g, which is applied over a washer g'. The upper end of the Bunsen burner is provided with an ordinary perforated cap G' and with a side 90 air-inlet opening g², while a rotary sleeve h, provided with knurled head or button h', turns upon the burner and is provided with a side opening h², adapted to register with the air-inlet opening g², so that more or less 95 air may be admitted to the Bunsen burner to commingle with the gas which passes thereto from the gas-bracket D. An illuminating-burner I is provided with a hollow jour-

nal I', which turns in a suitable bearing-sleeve I² at the outer end of the gas-bracket E. It will be observed in this connection that instead of employing the ordinary gas-cocks 5 which are arranged upon the gas-brackets the burners themselves are arranged to turn or rotate on their axes, and to limit the rotation to a half-turn the bearing-sleeve F is provided with abutments f f', against which a 10 radial stop-pin g³ on the burner abuts. A lateral opening g⁴, which passes through the journal F', corresponds with a point intermediate of the abutments, so that gas can pass through the said opening from the gas-bracket D, while the abutments correspond with the closed position, in which the gas is shut off. A similar arrangement is provided for the illuminating-burner.

For the purpose of turning the burners for 20 supplying or shutting off the gas there is applied to the hollow journal F' a perforated disk or button J, the outer edge of which is grasped in turning, while the illuminating-burner I is provided with a similar button or 25 disk J'. The gas-bracket E is shorter than D, so that the burners can be moved past each other.

It will be seen from the above detailed description that the gas-brackets can rotate or 30 swing around coincident centers, so that they can be adjusted either in oppositely-directed position, as shown in full lines in Fig. 2, or can be swung into the position shown in dotted lines, or in another position—that is to say, the 35 Bunsen and illuminating burners are adapted to be moved in parallel planes with respect to each other, according to the requirements. The gas always passes into the gas-bracket and is controlled directly at the burners by 40 the partial rotation of the same. This arrangement furnishes a very durable, efficient, and handsome appearance, and by reason of its simple construction, because the gas-cocks are dispensed with, it can be readily taken 45 apart and repaired or any part can be replaced when worn out.

Having thus described my invention, what I claim is—

1. The combination, with a suitable support, means for conducting gas thereto, and a bearing-sleeve on said support communicating with the interior thereof, of a radial gas-bracket having a journal arranged to turn in said bearing-sleeve and communicating with the interior of the support through suitable passages, and an additional gas-bracket swiveled on the first gas-bracket, substantially as set forth. 55

2. The combination, with a suitable support, means for supplying gas thereto, and a bearing-sleeve connected with said support, of a gas-bracket provided at one end with oppositely-projecting and aligned hollow journals communicating with each other and with the interior of the gas-bracket, one of said 65 journals being arranged to turn in said bearing-sleeve and having communication with the interior of the support, a Bunsen burner mounted on the gas-bracket, and an additional gas-bracket provided with an illuminating-gas burner and arranged to turn on the other journal, and communicating therewith, substantially as set forth. 70

3. In a gas-burner, the combination with the gas-bracket provided with a bearing, of a burner having a swivel provided with a lateral passage communicating with the burner, said swiveled burner being arranged to turn axially in said bearing and said lateral passage being adapted to register with the passage through the gas-bracket, and a button or disk arranged on the burner for imparting a partial rotation thereto, substantially as set forth. 75 80

In testimony that I claim the foregoing as my invention I have signed my name in presence of two subscribing witnesses.

ISIDOR BOORER.
